UNITED STATES PATENT OFFICE.

AMEDEO GIORGI, OF FLORENCE, ITALY.

MEANS FOR LIGHTING AND EXTINGUISHING GAS-LAMPS.

965,102.

Specification of Letters Patent. Patented July 19, 1910.

Application filed January 21, 1910. Serial No. 539,346.

To all whom it may concern:

Be it known that I, AMEDEO GIORGI, a subject of the King of Italy, residing at Florence, in the Kingdom of Italy, have invented new and useful Means for Lighting and Extinguishing Gas-Lamps, of which the following is a specification.

My invention relates to means for lighting and extinguishing gas lamps, and it consists 10 of an arrangement of valve wherein a ball, which closes the gas passage to the burner, is designed to be moved from its open or closed position by a striker when force is applied thereto outside the apparatus, while 15 at the same time the striker opens a passage for the gas to a suitable flash-lighting device, which passage remains open only while the pressure on the striker continues.

In the accompanying drawings: Figure 1 20 is a vertical section of an apparatus constructed according to my invention, for lighting and extinguishing gas lamps. Fig. 2 is a vertical section of the casing of the apparatus, showing more particularly the 25 seats for the ball. Fig. 3 is a sectional view of the tube which forms the passage to the flash lighting device. Fig. 4 is a plan of the casing and striker. Fig. 5 is a view similar to Fig. 1, showing the ball midway in its 30 travel between the two seats, after being struck.

In carrying out the invention, a casing α , is adapted to be screwed, at α^1 , on the gas service pipe and the cover α^2 of the casing, 35 to receive the burner fitting. On the floor of the casing α , are two seats b , c , the seat b being in direct communication with the gas supply, while the other seat c has no communication whatever, the ball m , of necessity 40 always resting on one or other of the two seats. In the side of the casing α , is screwed a short tube d , in which works a push-rod e carrying the striker f , which is so formed that it will move the ball m from either seat 45 to the other. The inner end of the push-rod e forms a valve at e^1 whereby gas is admitted into the tube d , so long as pressure is applied to the push-rod e , the said tube being in communication, through the hole 50 l , with the flash-lighting device. The outer end of the push-rod e carries a ring, or piston, g , which slides inside the tube d , and serves to prevent the escape of gas and to compress the controlling spring h which 55 tends to keep the valve closed.

The operation is as follows:—Supposing the ball m to be located in seat b so as to close the passage to the gas supply, if the push-rod e be struck, the ball will be knocked off its seat b on to the other seat c , and gas 60 will pass through the cover α^2 to the burner. At the same time, so long as pressure is applied to the push-rod e , the gas will pass to the lighting device through the tube d , which communicates therewith. When it is 65 required to extinguish the light, the striker f must be again operated, when the ball m will be knocked back on to the seat b communicating with the gas supply.

Having now described my invention, what 70 I claim, and desire to secure by Letters Patent, is—

1. In means for lighting and extinguishing gas lamps, the combination of a casing adapted for connection to the gas supply 75 pipe and having its floor provided with a pair of seats one of which has communication with said pipe; a valve adapted for reception in said seats; a striker arranged within the casing for shifting the valve from 80 either seat to the other; and means for operating said striker.

2. In means for lighting and extinguishing gas lamps, the combination of a casing adapted for connection to the gas supply 85 pipe and having its floor provided with a pair of seats, one of which has communication with said pipe; a ball adapted for reception in said seats; a striker arranged for movement into contact with the ball, said 90 striker having its ends curved for shifting said ball from either seat to the other; and means for operating said striker.

3. In means for lighting and extinguishing gas lamps, the combination of a casing 95 adapted for connection to the gas supply pipe and having a seat in its floor in communication with said pipe; a valve adapted for reception in said seat; a tube connected to the casing and in communication with the 100 interior of the latter and with a flash-lighting device; a striker arranged within said casing for removing said valve from said seat; and an operating member connected to said striker and slidably in said tube, said 105 member having its inner end constituting a valve, whereby gas is admitted through said tube to said flash-lighting device when said member is moved inwardly of said tube.

4. In means for lighting and extinguish- 110

ing gas lamps, a tube in communication with the flash-lighting device adapted to be inserted in the side of the casing and carrying a spring push-rod having a striker, the 5 inner end of the said push-rod forming a valve whereby gas is admitted into the tube during the application of pressure to the push-rod, and the outer end of the push-rod carrying a ring or piston which slides inside

the tube, substantially as and for the purpose set forth.

In witness whereof, I have hereunto signed my name in the presence of two subscribing witnesses.

AMEDEO GIORGI. [L. S.]
